UNITED STATES PATENT OFFICE.

ALBERT A. GOOSMAN, OF TECUMSEH, NEBRASKA.

DOOR OPENING AND CLOSING DEVICE.

Application filed November 22, 1924. Serial No. 751,585.

This invention relates to door opening means, the general object of the invention being to provide means whereby a vehicle about to enter a building or to leave the same will actuate means for opening and closing the door or doors thereof so that it is not necessary for a person to leave a vehicle to open and close the doors.

A further object of the invention is to provide means whereby the operating means within the building can actuate the door without operating the actuating means outside of the building and vice versa.

This invention also consists in certain other features of construction and in the combination and arrangement of the several parts, to be hereinafter fully described, illustrated in the accompanying drawings and specifically pointed out in the appended 20 claim.

In describing my invention in detail, reference will be had to the accompanying drawings wherein like characters denote like or corresponding parts throughout the several views, and in which:

Figure 1 is a front view of a building showing the invention in use, parts being broken away.

Figure 2 is a plan view with parts in section.

Figure 3 is a vertical sectional view taken through Figure 1.

Figure 4 is a detail sectional view of the differential means.

In these views, A indicates a building which is shown as a garage and B indicates the doors thereof which are slidably mounted on the tracks α . In carrying out my invention I arrange sprockets 1 on the shafts 2 and stretch an endless chain 3 over the sprockets, the upper stretch of the chain being connected with one door by a rod 4 and the lower stretch connected with the other door by the rod 4'. Thus as the chain is moved the doors will be caused to move towards each other or away from each other according to the direction of movement. Fluted rollers 5 are arranged in the driveway for the vehicle, one of these rollers being arranged within the garage and the other outside of the garage a distance from the front thereof. Each roller is arranged in a casing 6 in such a manner that it will be engaged by the wheels of the vehicle passing along the driveway and will thus be rotated

as the vehicle passes over the same. The bearings 7 for each roller are yieldingly supported by the springs 8 so that the roller will give slightly under the weight of the vehicle and will be frictionally held against the 64 wheels thereof. Small rollers 9 are arranged in the top of the casing, one on each side of each roller. A vertically arranged shaft 10 is geared to each roller by means of the beveled gears 11. The inner shaft 65 is connected by the gears 12 with one of the shafts 2 and the outer vertical shaft is connected by the gears 13 with a shaft 2', this shaft 2' and the outer vertical shaft being supported by the post 14. The sprocket 1' 70 at the left hand side of the building is made in the form of a casing and is rotatably mounted on the adjacent ends of the shafts 2 and 2' and these abutting ends carry the gears 15 which mesh with the beveled pinions 16 carried by the stub shafts projecting inward from the sprocket 1'. This arrangement constitutes a differential means so that the shafts 2 and 2' can rotate independent of each other so that the movement 75 of one roller 5 will not be communicated to the other roller 5. The shaft 2' is formed in two parts with clutch means 17 connecting the two parts together and a hand lever 18 is arranged to actuate the clutch 80 means. Thus the parts can be arranged so that the outer roller 5 will not operate the doors.

From the foregoing it will be seen that when a vehicle approaches the garage it will run over the outer roller, thus causing the same to rotate and the movement of this roller will be communicated through the shafts 10 and 2' to the differential means and through such means to the sprocket 1' which will actuate the chain 3 and thus open the doors so that the vehicle can enter the building. As its rear wheels pass over the inner roller the parts will be operated in a reverse direction so that the doors will be closed in rear of the vehicle. Then when the vehicle is to be backed out the inner roller 5 will be rotated by the reverse movement of the rear wheels of the vehicle in a direction 100 which will cause the doors to open and then as the vehicle passes over the outer roller the parts will be moved to close the doors again. 105

It will thus be seen that I have produced a simple means for opening and closing the doors of a garage or other building by a 110

vehicle without the driver or other occupant leaving the vehicle.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

In combination with a building and its door, a pair of sprockets, an endless chain passing over the sprockets, rods connecting the upper and lower reaches of the chains with the door, sectional shafts having one

section connected with one of the sprockets, a pair of rollers placed in the drive-way of the building and actuated by the wheels of a vehicle passing into the building or leaving the building, a vertical shaft geared to each roller, gears connecting the upper ends of the vertical shafts to the sectional shafts, clutch means connected to the said sectional shafts and preventing movement of the doors by the outer roller while the inner roller is being operated and retaining the inner roller against movement while the outer roller is being operated.

In testimony whereof I affix my signature.

ALBERT A. GOOSMAN.
